FIG. 1.

FIG. 2.

FIG. 3.

Inventor
Roy H. Brown
Lacey, Lacey, Attorneys

UNITED STATES PATENT OFFICE

ROY H. BROWN, OF CHESTER, ILLINOIS

TOY

Application filed April 26, 1929. Serial No. 358,311.

This invention relates to games and toys and more particularly to a toy adapted to be operated by a small child and afford amusement for the child.

5 One object of the invention is to provide a toy which, when in operation, will represent swimmers emerging from a tank and diving into the same.

Another object of the invention is to provide 10 the toy with a body portion constituting a mounting for the tank and so formed that it will be well supported and prevented from being liable to be easily turned over with resulting spilling of water if the tank is filled.

15 Another object of the invention is to so mount figures, constituting part of the toy, that when a shaft is rotated the toy figures will move in a circular path over and through the tank and while moving over the tank assume 20 positions naturally assumed by a person diving.

The invention is illustrated in the accompanying drawings, in which:

Figure 1 is a view showing the improved 25 toy in side elevation.

Figure 2 is a longitudinal sectional view through the toy.

Figure 3 is a transverse sectional view through the toy.

30 The body portion of this toy is formed from strong sheet metal and includes a bottom 1, side walls 2 and end walls 3, which extend upwardly from the bottom along margins thereof. The side and end walls may be formed integral with the bottom or from 35 separate sheets of metal and secured to the bottom and each other in any desired manner. The side and end walls converge upwardly from the bottom and their upper edges

40 terminate close to the upper edges of the side and end walls of a tank 4 which rests upon the bottom 1 of the body. This tank may be secured to the bottom or have its walls secured to the walls of the body so that it will 45 be held stationary in the body. Since the body projects from the sides and ends of the tank it will rest firmly upon a floor, table or other support upon which it may be placed and will not be liable to turn over when the

50 toy is in use.

Wings 5 project upwardly from the side walls at opposite sides of the tank intermediate the length thereof and these wings are formed with openings 6 so that they may serve as bearings to rotatably mount a shaft 7 which extends between the bearings transversely above the tank. This shaft 7 carries an arm 8 which projects radially therefrom between the bearings and at its outer or free end the arm 8 carries a cross head 9 which projects from its opposite sides transversely of the tank. By an inspection of Figure 3 it will be readily seen that when the shaft is rotated by means of its handle 10, the arm and its head will swing in a circular path and move longitudinally through the tank and then swing upwardly and downwardly above the tank in a direction longitudinally thereof.

The shaft 7, together with the arm 8 and its head 9, are formed from a single strand of strong wire which is bent intermediate its length to form an elongated loop constituting the head 9 and the end portions of the strand extend from the head intermediate the ends thereof in contacting relation to each other to form the arm 8. After the arm 8 has been formed, the end portions of the strand are bent away from the arm in opposite directions to form the shaft which passes through the openings 6 of the bearings or wings 5 and one end portion of the strand is then bent to form the operating handle 10. Collars 11 are fixed upon the shaft to bear the inner faces of the wings about the openings 6 and prevent the shaft from sliding longitudinally through these openings.

The toy figures 12 are also formed of sheet metal cut and painted so that they resemble a person diving and each figure is provided with a bearing 13 through which the outer cross bar 14 of the head 9 passes so that the figures will be loosely mounted upon this cross bar and permitted to have pivotal movement about the same when the shaft is rotated. It should be noted that the two figures are disposed at opposite sides of the arm 8 and are adapted to have contact with the inner portions 15 of the head 9 extending from opposite sides of the arm 8 so that pivotal movement of the figures about the outer cross bar

14 will be limited by engagement of the figures with the portions 15.

When the improved toy is in use, the tank 4 may be partially filled with water, if so desired, and the child grasps the handle 10 and rotates the shaft 7. As the shaft rotates the arm 8 and head 9 will swing in a circular path over and through the tank. As the arm swings upwardly the figures emerge from the tank and move upwardly as shown in Figure 1. When the arm is in its uppermost position, the lower portions of the figures engage the portions 15 of the head 9. Engagement of the lower portions of the figures with the portions 15 of the cross head will cause the figures to tilt forwardly and assume a position in which they appear to be diving into the tank as rotation of the shaft is continued. This position is shown in Figure 2. Continued rotation of the shaft will cause the figures to pass through the tank and then emerge again as shown in Figure 1. It will thus appear that two swimmers are simultaneously diving over the bearings longitudinally of the tank and into the tank.

What is claimed is:

1. A toy comprising a tank, a shaft rotatably mounted and extending across said tank, an arm extending from said shaft and having a head at its free end, a figure pivotally carried by said head and limited in its pivotal movement by engagement with a portion of the head, said figure having movement in a circular path over and through the tank when the shaft is rotated, and means to rotate said shaft.

2. A toy comprising a tank, bearings extending upwardly at opposite sides of said tank, a shaft rotatably carried by said bearings and extending across said tank, an arm extending radially from said shaft between said bearings, a head at the free end of said arm extending from opposite sides thereof longitudinally of the shaft, figures pivoted to said head at opposite sides of said arm and limited in their pivotal movement by engagement with portions of the head projecting from opposite sides of the arm, and means to rotate said shaft and cause the figures to swing in a circular path above and through the tank.

3. A toy comprising a tank, bearings extending upwardly at opposite sides of said tank, a shaft rotatably carried by said bearings and extending across said tank, an arm extending radially from said shaft between said bearings, a head at the free end of said arm having an outer cross bar and inner portions extending from opposite sides of the arm and supporting the cross bar, figures pivoted upon the cross bar and limited in their pivotal movement about the cross bar by contact with the portions extending from the arm, and means to rotate said shaft and cause

the figures to swing in a circular path above and through the tank.

4. A toy comprising a tank, bearings extending upwardly from opposite sides of said tank, a strand bent to form a flat loop constituting an elongated head and portions extending therefrom in contacting engagement with each other to provide an arm having the head at its outer end, the end portions of said strand being bent to extend from opposite sides of said arm and constitute a shaft journaled in said bearings and one end portion being bent to form a crank handle, and figures loosely mounted upon said head and limited in their pivotal movement by engagement with portions of the head when the shaft is rotated to swing the arm and move the figures in a circular path above and through the tank and simulate persons diving into the tank.

5. A toy comprising a body having a bottom and side and end walls extending upwardly therefrom, a tank resting upon the bottom of said body, the walls of the body sloping upwardly and at their upper ends contacting with the tank, bearings extending upwardly from the side walls of the body, a shaft journaled in said bearings and having turning means at one end, an arm extending radially from said shaft between said bearings, a head at the free end of said arm extending longitudinally of the shaft, and a figure pivotally carried by said head and having movement in a circular path over and through the tank when the shaft is rotated.

In testimony whereof I affix my signature.
